(57) **CLAIM**

The ornamental design for a fitness device as shown and described.

DESCRIPTION

FIG. 1 is a front perspective view of a fitness device showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and

FIG. 7 is a bottom plan view thereof; and,

FIG. 8 is an enlarged front view thereof in a folded state. The dashed broken lines in the drawings are for the purpose of illustrating unclaimed portions of the fitness device and form no part of the claimed design.

1 Claim, 8 Drawing Sheets
